UNITED STATES PATENT OFFICE.

ELIZABETH F. JOHNSON, OF NEW YORK, N. Y., ASSIGNOR TO J. M. WOODWARD, OF CLEVELAND, OHIO.

CIGARETTE-EXTINGUISHER.

No. 861,519.

Specification of Letters Patent.

Patented July 30, 1907.

Application filed January 26, 1907. Serial No. 354,190.

To all whom it may concern:

Be it known that I, ELIZABETH F. JOHNSON, a citizen of the United States, residing at New York city, in the county of New York and State of New York, have 5 invented a certain new and useful Improvement in Cigarette-Extinguishers, of which the following is a full, clear, and exact description.

The object of the present invention is to provide means whereby cigarettes may be readily and completely extinguished, and to so construct the extinguishing device that it may be placed and used upon 10 an ordinary table or in other positions where it may be convenient to have such an article.

As is well known to users of tobacco, it is the common 15 practice among cigarette smokers, when occasion arises to lay aside a burning cigarette, to merely place the same, still burning, in a smoker's tray provided for such purposes. If this should occur in a dining room or at a card table, the slow burning of the cigarette fills 20 the room with an obnoxious odor, which is excessively disagreeable. Frequently the person using the cigarette recognizes this fact and endeavors to extinguish the cigarette by pressing the lighted end down upon the tray, crushing or smearing the end over the tray 25 until the fire is extinguished. This may be more or less successful, depending upon the character of the tobacco in the cigarette and the manipulative skill of the smoker. But whether the smoker is successful in extinguishing the cigarette or not, he succeeds in 30 breaking and spreading the end of the cigarette until he has left an unsightly looking stub, besides, in all probability, burning or blackening his fingers. I have, however, devised a mechanism whereby the cigarette may be immediately and successfully ex- 35 tinguished without any of the disagreeable features noted above, and I have shown in the accompanying drawings an embodiment of my invention.

In the drawings, Figure 1 presents a perspective view of the extinguishing device. Fig. 2 is a detail 40 section showing the operative structure.

A frame or base A of any suitable design, character or construction is used to support the extinguishing device, and in the form shown I provide a cross arm A', on which the extinguishing device is mounted. Suitably secured to this cross arm is the base plate B of the extinguisher, which plate has a perforation B' at one end which may be surrounded by an upwardly projecting peripheral flange B², somewhat conical in shape, which serves to round off the edge of the opening. Projecting downwardly from this end of the plate is an extinguishing jaw B³ sufficiently rigid in construction for the purpose of operation. The sides of the plate B are curled back and under to form ways

B⁴ designed to receive a sliding plate C which reciprocates back and forth in these ways. This sliding 55 plate has projecting downwardly from the end near the opening B' an extinguishing jaw C' which is designed to coöperate with the stationary jaw B³ in crushing and extinguishing a cigarette held between these jaws. For the purpose of reciprocating the removable 60 jaw C' I provide a toggle composed of links D, D',—the link D being pivoted to ears projecting upwardly from the inner end of the plate C, and the link D' being pivotally held between ears at the outer end of the stationary plate B. A spring D² tends to throw the link 65 D' upwardly and hold the toggle in such position that the plate C, and consequently the jaw C' are in a retracted position, leaving an open space between the jaw C' and the jaw B³ into which the lighted end of a cigarette may be held.

I preferably provide one link of the toggle, as D', with a broad finger surface D³ designed to receive a pressure from the hand or one of the fingers, whereby the toggle may be pressed outward toward a more nearly straight position, and cause the jaw C' to advance 70 toward the jaw B³. This form of operating mechanism is the most powerful known, and by merely resting the weight of the hand or exerting a slight pressure upon the surface D³ it will be evident that the soft cigarette end may be crushed so that the fire there- 75 in will be entirely smothered immediately. Upon removing the pressure from the surface D³ the spring D² will immediately throw the toggle back into its normal position, and the cigarette stump may be allowed to fall through the jaws into the receptacle below. 80 85

Many modifications in details and in ornamentation may of course be made without departing from the spirit of my invention.

Having described my invention, I claim:

1. A cigarette extinguisher comprising two crushing 90 jaws mounted on a frame with a clearance between the same into which a cigarette may be advanced, and means whereby one of the jaws may be advanced toward the other.

2. A cigarette extinguisher comprising two crushing 95 jaws, one of which is movable toward the other, and a toggle attached to the movable jaw having a pressure receiving surface, whereby the link may be straightened out in such manner as to cause the movable jaw to advance toward the other jaw.

3. A cigarette extinguisher comprising a fixed jaw, and a movable jaw, said jaws shaped and positioned to form coöperating and crushing members, means for holding the movable jaw normally away from the fixed jaw, and hand operative means for advancing the movable jaw toward the fixed jaw.

4. A cigarette extinguisher comprising a supporting frame, a base plate supported thereby and having thereon a fixed jaw, a movable jaw adapted to be advanced toward said fixed jaw, and sliding ways rigid with said base plate, 110

a toggle, one link of which is attached to the movable jaw and the other link of which is attached to a part rigid with the base plate, said link being provided with a pressure receiving surface, and a spring mounted so as to hold the toggle in a position in which a movable jaw is normally retracted from the fixed jaw.

5. A cigarette extinguisher comprising two jaws shaped to crush a cigarette therebetween, means whereby relative movement between the jaws to bring their crushing sur-

faces together may be effected, and retracting means for separating the jaws and holding them in the position in which the cigarette may be inserted therebetween.

In testimony whereof, I hereunto affix my signature in the presence of two witnesses.

ELIZABETH F. JOHNSON.
